Primary Examiner — Vy Koenig*Assistant Examiner* — Omeed Agilee(74) *Attorney, Agent, or Firm* — Pearne & Gordon LLP(57) **CLAIM**

The ornamental design for a vacuum contact pad, as shown and described.

DESCRIPTION

FIG. 1 is a top perspective view of the first embodiment of a vacuum contact pad, showing our new design;

FIG. 2 is a top view thereof; the bottom view being identical;

FIG. 3 is a front view thereof; the rear, right and left views being identical;

FIG. 4 is an enlarged view of the area labeled 4 in FIG. 3 thereof;

FIG. 5 is a top perspective view of the second embodiment of a vacuum contact pad, showing our new design;

FIG. 6 is a top view thereof; the bottom view being identical;

FIG. 7 is a front view thereof; the rear, right and left views being identical; and,

FIG. 8 is an enlarged view of the area labeled 8 in FIG. 7 thereof.

The broken lines depict environmental subject matter only and form no part of the claimed design.

1 Claim, 4 Drawing Sheets(56)
